(57) **CLAIM**

The ornamental design for a combination golf utility tool and ball marker, as shown and described.

DESCRIPTION

FIG. 1 is an exploded frontal perspective view of a combination golf utility tool and ball marker incorporating my present invention;

FIG. 2 is an exploded front elevational view thereof;

FIG. 3 is an exploded rear elevational view thereof;

FIG. 4 is an exploded right side elevational view thereof;

FIG. 5 is an exploded left side elevational view thereof;

FIG. 6 is an exploded top plan view thereof;

FIG. 7 is an exploded bottom plan view thereof;

FIG. 8 is a rear perspective view thereof, showing the ball marker portion inserted for stowage in a receiving slot of the tool body portion;

FIG. 9 is an exploded rear perspective view thereof, relative to the view shown in FIG. 1; and,

FIG. 10 is a right side elevational view shown with an unclaimed golf ball in use for stenciling.

The broken line showing of a patterned stencil opening on the utility tool, the pattern on the front and rear of the ball marker, and the golf ball are included for the purpose of illustrating unclaimed subject matter and forms no part of the claimed design.
